UNITED STATES PATENT OFFICE

ROLLAND T. R. HASTINGS, OF HIGHLAND PARK, ILLINOIS

CARD-FILING SYSTEM

Application filed March 15, 1927. Serial No. 175,608.

This invention relates to file cards and to a system for using the same.

One object of my invention is to provide the cards with prospect and dealer and different commodity designations so that the manufacturer or the distributor or other user of the cards may, by removing portions of the cards at the designations, indicate when prospects become dealers, and thus readily know from the altered and intact cards which apply to dealers and which to prospects; thereby having at hand a convenient guide as to the development of the business and how to distribute sales literature to the best advantage.

A further object of my invention is to provide a series of drawers or like receptacles for receiving said cards, one drawer receiving all intact cards, which apply to prospects; and other drawers having interior arrangements to accommodate only altered cards, and thus prevent the dealer and prospect cards from being filed in the wrong drawers.

The invention consists further in the matter hereinafter described and claimed.

In the accompanying drawings:—

Fig. 1 is a front view of a filing card, ruled or marked off in accordance with my invention; and

Figs. 2 to 5 indicate how the cards are filed in different drawers at different times in accordance with my invention.

As shown in Fig. 1, the front face of the card 1 is marked off into three horizontal columns 2, 3, and 4. These columns are arranged one above the other and are marked or entitled "Sales matter mailed," "Follow up," and "Purchases," respectively.

Each of said columns is divided vertically into twelve squares, one for each month of the year, and so designated above the squares, as shown in Fig. 1. Each square is divided into two spaces or sections 5, 6. In the particular arrangement shown, these spaces or sections are formed by dividing the squares diagonally. The spaces or sections 5, 6 are devoted to different classes of merchandising, the letters "B" and "S" being marked therein on the drawing standing for "brushes" and "supports" (arch), respectively. The B's

are in all the upper sections 5 and the S's are in all the lower sections 6, although of course this arrangement could be reversed if desired.

The card 1, as shown in Fig. 1, is provided with four square or sharp corners, three of which, namely, the upper right-hand corner and the lower right and left-hand corners, are divided off by dotted or perforated lines 7, 7, as shown in Fig. 1. In the upper right-hand corner appears the letter "P" just above the dotted line 7, and below this line appears the letter "D"; while above the dotted line at the lower right and left-hand corners appear the letters "B" and "S", respectively. The letter "P" stands for "prospect," while the letter "D" stands for "dealer" and the letters "B" and "S" for "brush" and "support" (arch), respectively, as heretofore.

When advertising matter is to be sent out by mail to a prospect, a card such as 1 has the name and address of the prospect marked thereon above the uppermost of the horizontal rows 2, as shown in Fig. 1. If this literature relates to brushes, a check mark is made in a "brush" space 5 of the first row 2 in the month that the literature is mailed. The four corners of the card are left on and it is then filed in a card drawer, such as 8 in Fig. 2, said drawer being shaped to receive the card with its lower corners intact. If the literature related to arch supports, a check mark would be placed in one of the "S" spaces 6 under the appropriate month, as is apparent.

In the event that no sale immediately follows from the sending of this literature, follow-up literature is sent to the same prospect and a check mark is placed in one of the sections in the second row 3 under the month in which the follow-up matter was mailed. This mark is of course placed in the section corresponding to the character of merchandise covered by the literature. The card is then refiled in drawer 8 together with other prospect cards applicable to both classes of merchandise as covered by the cards.

If a sale follows from any of the literature previously mailed or sent out, then the prospect becomes a dealer of the particular class of merchandise covered by the literature, and

two corners of the card bearing his name are torn or cut off along the appropriate dotted or perforated lines 7. The upper right-hand corner of the card is one of the corners removed, to take off the "P" and leave the letter "D" to show that the party is now a dealer. If the merchandise purchased was brushes, the lower right-hand corner of the card is removed to show by "B" at this corner that the party is a dealer in brushes.

If the transaction covers arch supports, then of course the lower left-hand corner of the card is removed to show by the "S" at such corner the character of the merchandise. In addition to removing these corners, a check mark is placed in one of the appropriate squares of column 4 under the month covering the sale.

The cards are now filed in different drawers, those for brush dealers in drawer 9 of Fig. 3, and those for arch supports in drawer 10 of Fig. 4. As shown in these figures, triangular strips 11, 12 are fastened in the lower right and left-hand corners, respectively, of these drawers 9 and 10 to take up the spaces provided by removing the lower corners of the cards. Thus, all cards for brush dealers are filed in drawer 9, and all cards for arch support dealers are filed in drawer 10. By reason of the fact that the strips 11, 12 are at opposite sides of the drawers 9 and 10, the cards for one drawer will not fit in the other drawer. Should any of the cards be placed in the wrong drawer, the strips would cause the card to project up above the rest of the cards in the drawer and make the error manifest.

As subsequent purchases are made by the respective dealers, check marks are placed on the cards in column 4 in the different spaces under the months of such purchases, so that a ready and handy record may be had showing the number of these transactions throughout the year.

Should a dealer purchase both classes of merchandise as covered by the cards, then both lower corners of the card are removed and the card placed in drawer 13, as shown in Fig. 5. This drawer has two strips 14, 14 at its lower inner corners to occupy the spaces provided by removing both lower corners of the cards.

By the system and cards disclosed, a manufacturer or distributor can have a ready and convenient card record showing the number of dealers in the different merchandise handled, the amount of literature mailed out during the year or other period covered by the cards, as well as the number of purchases made by the dealers from time to time. From this record, the volume of business transacted with each of the various dealers can be kept at hand as a guide to the distribution of advertising and sales seeking and stimulating literature.

It is to be of course understood that my invention is not to be limited to altering only the corners of the cards, as they may be altered elsewhere and still be within the spirit and scope of my invention. Moreover, I do not wish to be limited to the two particular classes of merchandise mentioned, as my invention is applicable to other lines as well.

I claim as my invention:

1. A file card having a prospect and a dealer designation marked thereon at one corner and a different commodity designation marked thereon at each of two other corners so that the card is adapted to be structurally altered at the corners and will show whether it applies to a prospect or a dealer and the commodities dealt in, depending on whether its corners are intact or not.

2. A file card having dealer and prospect and different commodity designations marked thereon so that the card is adapted to be structurally altered at the same and will show whether it applies to a prospect or a dealer and the commodities dealt in, depending on whether the card is intact or not at such designations, said card also having a chart thereon enabling it to be shown when sales matter is distributed and sales made to either prospect or dealer or both.

In testimony whereof I affix my signature this 9th day of March, 1927.

ROLLAND T. R. HASTINGS.
